US00D630167S

(12) **United States Design Patent**
Donowho

(10) **Patent No.:** **US D630,167 S**
(45) **Date of Patent:** **** Jan. 4, 2011**

(54) **COVER FOR CABLE MANAGEMENT RACEWAY**

(75) Inventor: **D. Brian Donowho**, Austin, TX (US)

(73) Assignee: **Chatsworth Products, Inc.**, Westlake Village, CA (US)

(**) Term: **14 Years**

(21) Appl. No.: **29/353,951**

(22) Filed: **Jan. 16, 2010**

(51) **LOC (9) Cl.** **13-03**

(52) **U.S. Cl.** **D13/156; D13/155**

(58) **Field of Classification Search** **D13/155, D13/156, 184; D8/354-356, 360.1; D14/256, D14/299; 439/207-211, 445-447**

See application file for complete search history.

(57) **CLAIM**

The ornamental design for a cover for cable management raceway, as shown.

DESCRIPTION

FIG. 1 is an isometric view of a cover for cable management raceway, depicted in a vertical orientation, showing my new design;

FIG. 2 is a front view thereof;

FIG. 3 is a rear view thereof;

FIG. 4 is a bottom view thereof;

FIG. 5 is a top view thereof;

FIG. 6 is a left side view thereof; and,

FIG. 7 is a right side view thereof.
